TRAILER FOR A BICYCLE OR THE LIKE

Harry W. Trevena, 3974 Payne Ave.,
San Jose, Calif. 95117

Filed May 19, 1971, Ser. No. 145,115

Term of patent 14 years

Int. Cl. D12—10, 11

U.S. Cl. D90—1

FIG. 6

FIG. 7

FIG. 1 is a perspective view of the trailer or the like embodying the design;

FIG. 2 is a right side elevation thereof;

FIG. 3 is a left side elevation thereof;

FIG. 4 is a top plan view thereof;

FIG. 5 is a front elevational view thereof;

FIG. 6 is a rear elevational view thereof; and

FIG. 7 is an enlarged perspective view of the tow bar portion thereof.

The bicycle which is fragmentarily shown in broken lines in FIG. 1 is included for illustrative purposes only.

I claim:

The ornamental design for a trailer for a bicycle or the like, as shown and described.
